UNITED STATES PATENT OFFICE

FRANK SHADISH, OF BRIDGEVILLE, PENNSYLVANIA

TOY VEHICLE

Application filed June 13, 1932. Serial No. 616,979.

The present invention relates to new and useful improvements in toy vehicles in the form of miniature railroad cars or locomotives, street cars, automobiles, trucks, etc., and has for its primary object to provide, in a manner as hereinafter set forth, a toy of this character embodying a single truck or wheeled motor unit together with a plurality of various types or kinds of bodies which may be selectively and detachably mounted on the truck or wheeled motor unit.

Another very important object of the invention is to provide novel coacting means on the truck and the bodies for securing said bodies in position on the truck.

Other objects of the invention are to provide a toy vehicle of the aforementioned character which will be simple in construction, strong, durable, efficient and reliable in use, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation showing a miniature steam locomotive constructed in accordance with the present invention.

Figure 2 is a bottom plan view thereof.

Figure 3 is a view in side elevation showing a toy vehicle in the form of an electric locomotive.

Figure 4 is a view in side elevation of the truck.

Figure 5 is a view in bottom plan of the truck.

Figure 6 is a view in front elevation of the truck.

Referring now to the drawings in detail, it will be seen that the reference numeral 1 designates generally a truck which includes a metallic frame 2 which is substantially rectangular in plan. Axles 3 are journaled transversely in the frame 2 and have fixed on their end portions flanged wheels 4. The frame 2 of the truck 1 may have mounted

therein an electric or spring motor of any suitable construction (not shown) which may be operatively connected to one of the axles 3 in any desired manner, as by a train of gears. Pairs of vertically spaced fingers 5 project longitudinally from the rear end of the frame 2.

Projecting forwardly from the lower portion of the front end of the frame 2 is a horizontal lip 6. Above the lip 6, the front end of the frame 2 is provided with an opening 7 in which a latch 8 is operable. The latch 8 is pivotally mounted for swinging movement in a vertical plane on the interior of the frame 2 and on the front end of said frame, as at 9. A spring 10 is mounted on the inner side of the front end of the frame 2 and is engaged with the latch 8 for yieldingly urging said latch toward operative position. The latch 8 is provided with an angular handle 11 for manually swinging said latch to inoperative position against the tension of the spring 10.

The reference numeral 12 designates generally a body of suitable material, preferably metal, which may be formed to represent a steam or electric locomotive, as illustrated, a street car road or any other vehicle. The body 12 is of generally hollow construction for the reception of the truck 1, as illustrated 80 to advantage in Figure 2 of the drawings.

The shaft 13 is fixed transversely in the rear portion of the body 12 and is provided with a reduced intermediate portion 14 which is slidably insertable between the upper and lower fingers 5 of the frame 2. The reduced portion 14 of the shaft 13 provides shoulders 15 which substantially prevent sliding movement of the shaft 13 laterally with respect to the truck 1. The reference numeral 16 designates a shaft similar to the shaft 13 which is fixed transversely in the forward portion of the body 12. The shaft 16 is engageable on the lip 6 of the frame 2 for supporting the forward end portion of the body 12 on the truck 1. The shoulders provided by the reduced intermediate portion of the shaft 16 are engageable with the ends of the lip 6 to prevent lateral movement of the forward end of the body 12 relative to the truck. The latch 100

8 is engageable with the shaft 16 for retaining said shaft 16 on the lip 6.

It will thus be seen that I have provided a construction and arrangement through the medium of which various types of bodies may be expeditiously mounted on the truck and removed therefrom. To mount the body on the truck, the shaft 13 is inserted between the fingers 5 and said body is then swung downwardly until the shaft 16 passes the latch 8 and engages the lip 16. The shaft 16 travels closely adjacent the front end of the frame 2 and said front end is curved upwardly as best suggested in Figure 4 of the drawings to conform to the arc described by said shaft 16 during this swinging operation. To remove the body from the truck, the latch 8 is swung to inoperative position against the tension of the spring 10 by engaging a finger or thumb with the handle 11, thus releasing the shaft 16 for upward swinging movement until it clears the frame 2, after which the shaft 13 may be slipped rearwardly from between the fingers 5.

As previously stated, a spring or electric motor, (not shown) may be carried in the frame 2 of the truck. If an electric motor is used, electric lights (not shown) may be provided in the body 12 and electrically connected with said electric motor by means including a metallic contact plate 17 which is mounted in the forward upper portion of said body 12 and insulated therefrom, said contact plate 17 being engageable with a resilient contact finger 18 which is electrically connected with the electric motor.

It is believed that the many advantages of a toy vehicle constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A vehicle comprising a wheeled truck, a body, and means for removably mounting the body on the truck, said means including spaced fingers on the truck, and a shaft on the body engageable between the fingers, said shaft having a reduced intermediate portion providing shoulders adjacent the fingers, said shoulders engageable with the fingers for retaining the body against lateral movement on the truck.

2. A vehicle comprising a wheeled truck, a body, vertically spaced fingers projecting from one end portion of the truck, a shaft mounted transversely in one end portion of the body engageable between the fingers, said shaft having a reduced intermediate portion providing shoulders adjacent the fingers, said shoulders engageable with the fingers for

retaining the body against lateral movement on the truck and coacting means on the other end portion of the truck and on the body for releasably securing said body to the truck.

3. A vehicle comprising a wheeled truck, 70 a body, vertically spaced fingers projecting from one end portion of the truck, a shaft mounted transversely in one end portion of the body engageable between the fingers and coacting means on the other end portion of the truck and on the body for releasably securing said body to the truck, said means including a support on the truck, another shaft on the body engageable on the support, and a latch on the truck engageable with the second named shaft for retaining said second named shaft on the support. 75 80

4. A vehicle comprising a wheeled truck, a body, and means for removably mounting the body on the truck, said means including a lip projecting from the truck, a shaft mounted on the body and engageable on the lip, and a latch mounted on the truck and engageable with the shaft for releasably securing said shaft on the lip. 85 90

In testimony whereof I affix my signature.

FRANK SHADISH.
